UNITED STATES PATENT OFFICE.

JOHN KRALUND, OF BROOKLYN, NEW YORK, ASSIGNOR TO DOEHLER DIE CASTING COMPANY, OF BROOKLYN, NEW YORK, A CORPORATION OF NEW YORK.

TURNTABLE FOR TALKING MACHINES.

Application filed October 30, 1920. Serial No. 420,779.

To all whom it may concern:

Be it known that I, JOHN KRALUND, a citizen of the United States, residing in the borough of Brooklyn, city of New York, county of Kings, and State of New York, have invented certain new and useful Improvements in Turntables for Talking Machines, of which the following is a specification.

10 My invention relates to an improved form of turntable for talking machines, upon which the usual disc records are adapted to be positioned. The turn-tables as now manufactured tend to run out of true, because of uneven distribution of the metal therein or for other causes. My invention is designed to produce a turn-table which shall be of light construction, inexpensively made, readily assembled and of attractive 20 appearance and with the further advantage that the same should at all times rotate in a horizontal plane without deviation.

I achieve these results by the provision of a spider having hub and rim portions and portions connecting the same, in which the metal is evenly distributed and which is of sufficient rigidity to maintain its shape at all times. This spider is preferably formed by the die-casting process, by which a maximum of uniformity may be secured. This spider is preferably formed of aluminum or other light metal.

A thin metal disk is mounted upon the spider and a covering of felt or the like, such as is usually used upon talking machine turn-tables, is secured upon this disc. The disc is preferably secured to the spider by means of clips formed on or punched from the disc, which are extended through 10 suitable openings in the spider and bent to position to hold the disc flat upon the spider. The felt covering is preferably stretched over the metal disc and secured thereto by means of prongs on the edge of the disc, which pass through the edge portion of the felt and are turned over on the under side. A peripheral recess is preferably provided upon the upper face of the spider, adjacent to the outer rim portion, and the turned over edge of the felt cloth and the prongs referred to are received within this recess.

In order that a clearer understanding of my invention may be had attention is here- 55 by directed to the accompanying drawings

forming part of this application and illustrating one form of my invention. In the drawings Fig. 1 represents a side elevation of a turn-table embodying my invention, parts being shown broken away and parts shown in section, Fig. 2 is a partial bottom plan view of the same, Fig. 3 is an enlarged partial vertical section taken on line 3-3 of Fig. 2, Fig. 4 is a partial vertical section through the rim portion of the construction taken on line 4-4 of Fig. 2 drawn to a further enlarged scale and Fig. 5 is a partial enlarged bottom plan view of the metal disc with the cloth covering thereon.

Referring to the drawings the spider 1 is preferably a metal casting, preferably a die-casting of aluminum or other desired metal having a central hub 2, a peripheral rim 3 and radial arms 4 connecting the hub and rim. A web portion 5 is also shown as connecting the hub and rim. The construction is so made as to provide an equal distribution of the metal in all directions radially from the centre. The hub 2 is provided with a central vertical opening 6 through which the rotating spindle of the talking machine may be inserted in the usual manner, a sleeve 7 being mounted in opening 6 if desired.

A thin metal disc 8 is provided which may suitably be formed of tin plate. This disc is provided with a plurality of downwardly extending clips 9 which may suitably be formed by punching the same from disc 8. The spider 1 is provided with a plurality of openings 10 therethrough through which clips 9 are adapted to extend. These openings are preferably formed adjacent to the arms 4 of the spider so that the clips 9 may be turned over into binding engagement with arms 4.

A covering 11 of felt cloth or other suitable material is stretched over and secured upon the upper surface of disc 8. The latter is preferably provided with pointed prongs 12 formed about the edge of the same to extend radially. When the felt disc 11 has been stretched over the metal disc it is secured in place by the prongs 12 which extend through the felt, the latter having its edge portion turned under the edge of the metal disc 8, as is shown at 11', the prongs 12 then being bent inwardly beneath the edge portion 11' of the felt.

The spider 1 is provided with a peripheral

recess 13 in which the edge portion 11' of the felt and the prongs 12 are received when the device is assembled.

In assembling the device, the felt covering 5 is secured upon the metal disc 8 whereupon the latter is positioned on the spider with clips 9 extending through openings 10 after which the clips are turned over to secure the metal disc with its covering to the arms of 10 the spider. When so mounted, the metal disc will lie flat upon the upper surface of the spider, the upper surface of the felt covering being in horizontal alignment with the upper surface of rim 3, the disc 8 being 15 of a suitable diameter so that this disc with its felt covering will fit within the upwardly extending rim portion 3' as shown.

It should be understood that my invention is not limited strictly to the exact details of construction described but is as broad as is indicated by the accompanying 20 claims.

What I claim is:

1. A turn-table for talking machines, 25 comprising a spider having hub and rim portions; a disc secured on the upper face of said spider, having prongs extending about its edge, and a cloth disc stretched over

said disc, said prongs being extended through the cloth disc and bent over to secure the same in position.

2. A turn table for talking machines, comprising, in combination, a spider having hub, rim and web portions and openings through said web portions, a metal disc supported on said spider and having clips extending through said web openings and bent to secure said disc to said spider.

3. A turn table for talking machines, comprising, in combination, a metal disc, a cover member stretched over said disc and doubled under the edge thereof, prongs about the edge of said metal disc penetrating said doubled under portion of said cover member and bent to secure the same to said disc, and a spider in supporting position below said disc, said spider having a horizontal supporting surface and an annular recess for said doubled under portion of said cover member and for said securing prongs.

This specification signed and witnesses this 27th day of October, 1920.

JOHN KRALUND.
